UNITED STATES PATENT OFFICE

ADOLF RIST, OF BERLIN, GERMANY, ASSIGNOR TO THE NATIONAL CASH REGISTER COMPANY, OF DAYTON, OHIO, A CORPORATION OF MARYLAND

CASH REGISTER

Application filed November 2, 1928, Serial No. 316,787, and in Germany November 18, 1927.

This invention relates to cash registers or similar machines, and is more particularly related to novel locking mechanisms whereby certain of the functions of such machines may be controlled.

For illustrative purposes, the invention, in its preferred form, is attached to a machine of the type disclosed in Letters Patent of the United States, No. 1,242,170, issued October 9, 1917 to F. L. Fuller, and Nos. 1,619,796 and 1,655,570, issued March 1, 1927 and January 10, 1928, respectively, to B. M. Shipley.

Machines of this type are usually equipped with a plurality of groups of totalizers, and a manipulative control means, as a lever, having an intermediate adding position and a plurality of zeroizing positions on opposite sides of the adding position, the lever being normally located in its adding position to control the machine to add onto totalizers, but shiftable therefrom in either direction to control mechanism to reset the several totalizers to zero. When moved from its "add" position to its zeroizing positions, the total control lever, as it will be hereinafter referred to, determines from which of a plurality of groups of totalizers, a single selected totalizer is to be reset to zero. In its adding position, the total lever, of course, controls the machine to accumulate amounts on any selected totalizer.

It is old to provide a lock or locks with which to retain the total control lever in its adding position, or as stated differently, to lock the lever out of its zeroizing positions, to prevent unauthorized clerks from resetting certain of the totalizers to zero. The proprietor usually retains possession of the key to the total lever lock, the withdrawal of which renders certain of the zeroizing positions accessible to the total control lever. As often happens, however, after resetting the totalizer or totalizers to zero, and after returning the total control lever to its adding position, the proprietor may forget to turn the lock to prevent the unauthorized re-adjustment of the lever back to one or another of its zeroizing positions.

One object of this invention is to provide a novel locking mechanism in combination with

such a control lever whereby the proprietor or other authorized person is forced to render the zeroizing positions inaccessible to the lever before the control lever can be restored to its adding position. The usual locking mechanism prevents operation of the machine unless the lever is in one or another of its predetermined positions, nor can any amount keys be depressed while the lever is out of its "add" position.

This object is effected by so arranging the lock relatively to the control lever, that the latter must be shifted out of its "add" position before the zeroizing position or positions can be rendered accessible, and vice versa. The zeroizing position or positions must be rendered inaccessible before the control lever can be fully restored to its "add" position.

Another object is to provide novel means to count the number of times the total control lever is moved into any certain position.

With these and incidental objects in view, the invention includes certain novel features of construction and combinations of parts, the essential elements of which are set forth in appended claims and a preferred form or embodiment of which is hereinafter described with reference to the drawings which accompany and form a part of this specification.

In said drawings:

Fig. 1 is a view in front elevation, showing the locking device and the counter for counting the number of times the total control lever is moved into its lowermost resetting position.

Fig. 2 is a fragmentary detail view of the lock and locking plate.

Fig. 3 is a fragmentary view in side elevation, of the counting device for use in connection with the total lever.

The invention is applicable to a keyboard mechanism of the kind illustrated in the Shipley Patent, No. 1,655,570. In that machine, the total control lever has an intermediate adding position, three positions below the adding position, and three positions above the adding position. When the total control lever is shifted to any of its positions below the adding position, it sets mechanism

to select the desired group of totalizers in which is included the particular totalizer to be cleared, and also sets mechanism to control the machine to reset or clear the selected totalizer. When the total lever is shifted to any of the positions above the adding position in the Shipley patent, it also sets the mechanism to select the desired group of totalizers, and also sets the mechanism to control the machine to take a sub-total from the particular totalizer of the selected group. Since the present invention may be completely disclosed by illustrating its application to the lower series of positions to any of which the total control lever may be adjusted, together with the "add" position, the upper series of positions is not illustrated herein, and no description thereof is included in this specification. The mechanism embodying this invention may be conveniently duplicated for the upper series of positions.

The total control lever 25 (Fig. 1) projects from the usual total control plate 24 (Fig. 3) disclosed in the prior art cited, which plate is suitably supported to enable the operator to shift the lever vertically along a slot 27 (Fig. 1) in an index plate 28.

The total lever 25 normally rests in a recess or index notch 26 formed intermediate the ends and on one side wall of the slot or way 27 in the index plate 28. Other notches are provided both above and below the intermediate notch 26. However, only those notches which are located below the intermediate notch 26 are shown herein. These notches 29, 30 and 31 are for the purpose of locating the total control lever 25, and holding it in its various positions to condition the machine for adding and for resetting or clearing the totalizers of the several lines or groups.

When the total control lever 25 is shifted to the first position 29 below the adding position 26, it automatically controls the selection of the series of clerks' totalizers for operation, and the engagement and disengagement of a selected one of such totalizers relatively to the usual actuators (not shown). Neither the totalizers nor the mechanism by which the lever 25 controls them are shown herein, as the invention is directed to means for locking the total control lever 25 out of certain of its positions.

The lever 25 is free to be shifted from its "add" position to the position 29 wherein it selects the group of clerks' totalizers and, after resetting the particular one of the clerks' totalizers or all of said totalizers, the lever 25 is shifted back to its "add" position. However, movement of the total control lever 25, to the second position 30 wherein it selects the group of department totalizers, or to the third position 31 wherein it selects the group of transaction totalizers, is normally blocked by a blocking bar 33, which lies just beneath

the slotted plate 28, and is of a length sufficient to extend across both notches 30 and 31. The normal position of this blocking bar 33 is as shown in Fig. 1, wherein it extends across the slot 27 and in the path of the total control lever 25, constituting an obstruction to prevent adjustment of the lever to either of its positions 30 or 31. Obviously, if desired, the blocking bar could be extended to prevent adjustment of the total control lever 75 to the position 29. A link 34 pivoted at one end to the blocking bar 33 intermediate its ends, is eccentrically pivoted at its opposite end to a lock barrel 35, (Fig. 2), suitably supported on a frame (not shown). The outer 80 end of the barrel 35 extends through a suitable aperture in the index plate to be accessible to the proprietor who may, by inserting the proper key and turning the barrel 35, draw the blocking bar 33 to the right and out of line 85 with the slot 27, thereby permitting adjustment of the total control lever 25 to the lower two positions 30 and 31. Studs 36 and 37 projecting inwardly from the index plate 28 guide the blocking bar 33 as it is shifted to and from its effective position, the studs 37 bracing the bar against pressure applied to the opposite end of the bar through the lever 25, when the bar is in effective position.

Other studs 38 and 39 in the index plate 95 limit the movement of the blocking bar 33 towards the right.

After the total has been taken from any one, or a plurality of the department or transaction totalizers, and before the total control lever 25 can be restored to its adding position, it is desirable to compel the proprietor to turn the lock 35 in order to again position the blocking bar 33 in the path of the total control lever 25 to prevent re-adjustment of the lever to the total taking positions 30 and 31. The reason for this is, that should the proprietor neglect to lock the total control lever out of its department and transaction total taking positions, any of the clerks 110 or any unauthorized person might zeroize any of the department or transaction totalizers at will.

To accomplish the above purpose, a link 45 connects one arm 46 of a bell crank 47, 115 pivoted on a stud 48 in the index plate 28, to the blocking bar 33, the remaining arm of the bell crank lever terminating in a nose 49 normally located adjacent the "add" position of the total control lever. With the parts in their normal positions shown in Fig. 1, the proprietor wishing to take one or more totals from the department or transaction totalizers or both, will first adjust the total control lever 25 from its "add" position 26 towards 120 the positions 30 and 31, and may advance the lever until it contacts and is arrested by the upper end of the blocking bar 33. It is only necessary, as will hereinafter appear, to dislodge the lever from its "add" position, how- 125 130

ever. The proprietor will then insert his key in the lock barrel 35 and turn the key, and the barrel to withdraw the blocking bar 33 from the path of the lever which may then be advanced to either of the total taking positions 30 or 31 and the machine operated.

The blocking bar 33, on its withdrawal from the path of the total control lever 25, operates the link 45 to rock the nose 49 of the bell crank lever 47 across the guide slot 27 at the point where the lever stands for permitting adding, to block the restoration of the total control lever to its "add" position so long as the blocking bar 33 remains in its withdrawn or idle position.

Consequently, should the proprietor become forgetful and attempt to return the total control lever directly to its "add" position, the lever will contact the nose of the bell crank 47, which prevents access of the lever to the "add" position, and the arrest of the lever apprises the proprietor of the fact that he has not restored the blocking bar 33 to its normal effective position. Thereupon, while the lever is out of the path of the blocking bar 33, the proprietor will operate his key and reversely rotate the lock barrel 35 to restore the blocking bar and render the positions 30 and 31 inaccessible to the lever.

At the same time, the link 45 connecting the blocking bar 33 and bell crank 47, rocks the latter to withdraw the nose 49 of the bell crank from its locking position relatively to the lever 25 and the "add" position 26, whereupon, the proprietor completes the restoration of the total control lever to its normal "add" position, and the machine is in condition for operation by the clerks.

Should the proprietor attempt to withdraw the blocking bar 33 by rotating the lock barrel 35, before displacing the total control lever 25 from its "add" position, the operation will be arrested before the complete withdrawal of the blocking bar to idle position, because of the contact of the nose 49 of the bell crank 47 with the total control lever 25 which arrests the bar 33 before it has cleared the slot 27. It is necessary, therefore, to move the total control lever 25 to a position between the notch 26 in the adding position and the end of the blocking bar 33 before the lock 35 can be turned sufficiently to remove the blocking bar 33 from the path of the lever 25.

To count the number of times the total control lever 25 is adjusted into the notch 31, for instance, to control the machine to zeroize one of the transaction totalizers, a Veeder type consecutive counter 55 is provided. An operating crank 56 fast on the counter shaft 57 of the consecutive counter lies in the path of the total control lever 25, so that when the lever 25 is shifted to its lowermost position, it contacts with and rocks the crank 56 clockwise to the position shown by dot and dash

lines in Fig. 3. A spring 58 attached to the crank 56 restores the latter to its normal position when the total control lever 25 is shifted away from the crank.

While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.

What is claimed is:

1. In a machine of the class described, the combination with a reciprocating manipulative member adjustable between two positions; of blocking means normally effective to prevent the adjustment of the manipulative member from one to the second of its positions; and means connected with the blocking means and operable upon the manipulative member to compel the displacement of the manipulative member from the first of its positions before the second of its positions can be rendered accessible to it.

2. In a machine of the class described, the combination with a reciprocating manipulative member adjustable between two positions; of blocking means normally effective to prevent the adjustment of the manipulative member from one to the second of its positions; and means shiftable into the path of return of the manipulative member upon the withdrawal of the blocking means to ineffective position, to prevent the restoration of the manipulative member to the first of its positions while the blocking means for the second of such positions remains ineffective.

3. In a machine of the class described, the combination with a reciprocating manipulative member having a normal position and at least one other position between which it is adjustable; of means to normally block the manipulative member from said position other than normal; means to withdraw the blocking means; and means operable by said withdrawing means to block the manipulative member from adjustment to its normal position.

4. In a machine of the class described, the combination with a reciprocating manipulative member having a normal operative position and at least one other operative position; of means to block the manipulative member from adjustment to its operative position other than normal; means to enforce movement of the manipulative member from its normal position before said blocking means can be rendered ineffective, and to enforce movement of the blocking means to its effective position before said manipulative member can be restored to its normal position; and means to operate said blocking means and said enforcing means.

5. In a machine of the class described, the combination with a shiftable total control lever having an adding position and a totalizing position; of a blocking bar to prevent access of said lever to its totalizing position; means to withdraw said blocking bar to idle position and to restore it to effective position; and means to compel movement of the total control lever from its adding position before the blocking bar can be withdrawn.

6. In a machine of the class described, the combination with a total control lever having an adding position and a totalizing position; of a blocking bar to prevent access of said lever to its totalizing position; means to operate said blocking bar; and means actuated by said operating means to compel movement of the total control lever out of its adding position before said blocking bar can be withdrawn to render the totalizing position accessible, and to compel restoration of said blocking bar before the lever can be restored to its adding position.

7. In a machine of the class described, the combination with an adjustable member having an adding position and a totalizing position; of a blocking device to prevent adjustment of the member to its totalizing position; means operable to withdraw said blocking device to render the totalizing position accessible to the adjustable member; and a lever connected to said blocking device and adapted to contact the adjustable member to prevent operation of the operable means to withdraw the blocking device until the adjustable member is moved from its adding position.

8. In a machine of the class described, the combination with an adjustable member having an adding position and a totalizing position; of a blocking device to prevent adjustment of the member to its totalizing position; means operable to withdraw said blocking device to render the totalizing position accessible to the adjustable member; and a lever connected to said blocking device and adapted to contact the adjustable member to prevent operation of the operable means to withdraw the blocking device until the adjustable member is moved from its adding position, said lever being operable as the blocking device is withdrawn to ineffective position, to prevent the return of the adjustable member to its adding position until the blocking device is restored to its effective position after the displacement of the adjustable device from the totalizing position.

9. In a machine of the class described, the combination with an adjustable member having two positions to either of which it may be adjusted; a blocking element normally lying in the path of the adjustable member to prevent access thereof to one of such positions; and means to render the blocking element effective and ineffective; of a normally idle

auxiliary locking lever; a link to connect the blocking element and the locking lever, one arm of the locking lever adapted to intersect one of the positions occupied by the adjustable member, and to prevent its return thereto when the blocking element is rendered ineffective.

10. In a machine of the class described, the combination with a manipulative member having a normal operable position and two other operative positions; of means to block the manipulative member from adjustment to one of its operative positions; means to enforce movement of the manipulative member from its normal position towards another of its operative positions before the blocking means can be rendered ineffective, and to enforce movement of the blocking means to its effective position before the manipulative member can be restored to its normal position; and means to operate said blocking means and said enforcing means.

11. In a machine of the class described, the combination with a reciprocating manipulative member adjustable, preceding an operation of the machine, between two positions; of blocking means operable to enforce the manipulative member, during such preliminary adjustment, to be shifted into a position intermediate said two positions prior to the adjustment of the manipulative member from either of its positions into its other position.

In testimony whereof I affix my signature.
